EVAPORATOR

Bernard C. Johnson, Libertyville, and Edgard C. Franco-Ferreira, Chicago, Ill., assignors to Houdaille-Hershey Corporation, Detroit, Mich., a corporation of Michigan

Application May 10, 1940, Serial No. 334,306

8 Claims. (Cl. 62—126)

This invention relates to sheet metal heat exchangers such as evaporator units for mechanical refrigerators and more specifically relates to wick constructions in evaporator units for automatically returning oil entrained in refrigerant in the evaporator unit back to the compressors of the mechanical refrigerating systems.

In refrigerating systems of the compressor-condenser-evaporator type, oil from the compressor finds its way with the refrigerant to the evaporator unit. Many devices have been proposed for trapping this oil in order that the same can be returned to the compressor for performing its lubricating function. Such devices, however, have been expensive and complicated.

The present invention now provides a simple, inexpensive wick means for returning oil from evaporator units back to the compressor without short-circuiting the refrigerant flow or in any way causing the flow of refrigerant back to the compressor before it has completed its heat-absorbing function.

The wick means of the present invention are especially adapted for use in refrigerating systems employing sulphur dioxide as a refrigerant. The lubricating oil used in such systems will not dissolve in the sulphur dioxide to any great extent at the evaporator temperature. Accordingly, it has now been found that the use of a simple wire wick between the evaporator unit headers and the suction line of the mechanical refrigerating system will efficiently return the oil to the compressor without in any way affecting the working conditions of the evaporator.

While the invention will be hereinafter described and illustrated in connection with embossed sheet metal evaporator units, it should be understood that the wire wick means for returning oil to the compressor is adapted for use in other types of evaporator units including the type built up from tubes and headers.

A feature of the invention includes the embossing of sheet metal evaporator units to receive the wire wick oil returning means.

It is, then, an object of the invention to provide heat exchangers, such as evaporator units, with simple, inexpensive oil returning means.

Another object of the invention is to provide a wire wick device for returning oil from the headers of evaporator units into the suction lines of a mechanical refrigerating system.

A further object of the invention is to provide embossed sheet metal evaporator units having wick means embodied therein for discharging oil

from the unit without discharging liquid refrigerant therewith.

A specific object of the invention is to provide a device for removing oil from liquid refrigerant by capillary action without loss of refrigerant.

Another object of the invention is to interpose a device between a header and a suction line of an evaporator unit for effecting transfer of oil from the header to the supply line by capillary action without effecting removal of liquid refrigerant therewith.

Other and further objects of the invention will become apparent to those skilled in the art from the following detailed description of the annexed sheets of drawings which disclose preferred embodiments of the invention.

On the drawings:

Figure 1 is a diagrammatic elevational view of a mechanical refrigerating system of the compressor-condenser-evaporator type, including an evaporator unit according to the invention.

Figure 2 is an enlarged top plan view of the evaporator unit shown in Figure 1 taken along the line II—II of Figure 1.

Figure 3 is a side elevational view of the evaporator unit shown in Figure 2 taken along the line III—III of Figure 2.

Figure 4 is an enlarged vertical cross-sectional view, with parts in elevation, taken along the line IV—IV of Figure 2.

Figure 5 is a fragmentary end elevational view taken along the line V—V of Figure 3.

Figure 6 is a small plan view of a woven mesh material illustrating the manner in which the same is rolled into the wick shown in Figure 4.

Figure 7 is an end elevational view of a modified form of evaporator unit equipped with a wire wick oil returning means according to this invention.

Figure 8 is a fragmentary plan view, with parts in horizontal section, taken along the line VIII—VIII of Figure 7.

As shown on the drawings:

In Figure 1 the reference numeral 10 designates a base or support for an electric motor 11 and a refrigerant compressor 12. The motor 11 drives the compressor 12 through a belt 13.

Compressed refrigerant from the compressor 12 flows through a tube or conduit 14 into a condenser 15 where it is cooled and condensed into liquid form. The condensed refrigerant then flows through a tube or conduit 16 into a receiver tank 17 from which it is directed, as needed, into a valve 19 which injects liquid refrigerant, as needed, through a tube 20 into the shelf

tube 21 of an evaporator unit 22. The refrigerant flowing through the shelf tube 21 cools the shelf and is directed through a tube 23 into an embossed header 24 on the bottom of the evaporator unit 22. The header 24 communicates with a plurality of embossed expansion ducts 25 extending around the sides and bottom of the evaporator unit and the refrigerant circulates through the ducts 25 into the headers such as 26 on each side of the unit. A suction conduit 27 is embossed on the sides and bottom of the evaporator unit and communicates with the suction line 28 back to the inlet side of the compressor 12. According to this invention wire wick means such as 29 are interposed between the headers such as 26 and the tops of the suction conduit 27 for removing oil from the liquid refrigerant in the headers without removing liquid refrigerant therewith. The suction line 28 thus receives gasified refrigerant and oil from the evaporator unit. The oil is thus returned to the compressor for performing its lubricating function while the gasified refrigerant is compressed by the compressor and returned for re-condensation in the condenser unit.

As best shown in Figures 2, 3 and 5, the evaporator unit 22 is composed of a pair of brazed-together metal sheets bent in substantially U-shape to provide vertical side walls and a horizontal bottom of a sharp freezing chamber. The tops of the vertical walls are bent inwardly to form horizontal flanges 30 adapted for attachment to the roof of a refrigerator cabinet so as to suspend the unit in the top of the cabinet.

The outer sheet of the unit 22 is embossed to form the header duct 24 extending longitudinally along the bottom of the unit. The outer sheet is also embossed to form the expansion ducts 25 extending in spaced parallel relation from the header 24 to the tops of the side walls. Both the inner and outer sheets are further embossed to form elongated cylindrical headers 26 extending longitudinally along the tops of the side walls of the unit and communicating with the tops of the expansion ducts 25. The expansion ducts 25 terminate in the bottoms of the headers 26.

The suction duct or discharge duct 27 of the evaporator unit is embossed in the outer sheet of the unit and extends from the tops of the side walls around the sides and bottom of the unit to an embossed dome-like portion 31 on the inside sheet of the unit. The suction duct 27 does not communicate with the header 24 as illustrated in Figure 5 but discharges into the dome portion 31 which receives the suction line 28 communicating with the inlet side of the compressor 12 as explained above.

In this form of evaporator unit, therefore, the suction or return duct is embossed in the unit and extends around the sides and bottom of the unit so that it can be exhausted through a single tube leading to the compressor unit. The embossed suction duct 27 receives gasified refrigerant from the tops of both headers 26 through embossed ducts 32 on the inner sheet of the unit. Each of these ducts joins the top of a header 26 with the top of a vertical leg of the suction duct 27.

A sheet metal shelf 33 bridges the interior of the evaporator unit 22 in spaced relation from the bottom thereof. The shelf has downturned flanges 33a which are riveted as at 34 to the side walls of the unit. The shelf also has a dependent flange 33b at the rear end thereof to act as a

stop for articles mounted on the bottom wall of the unit. Upturned flanges 33c are also provided at the rear end of the shelf 33 to act as stops for ice trays or other articles mounted on top of the shelf.

In order to cool the shelf 33 the inlet tube 20 from the valve 19 described in Figure 1 communicates with a tube 21 secured to the underside of the shelf 33. The shelf can be embossed as at 33d to receive the tube 21. A single loop of the tube as shown in Figure 2 is sufficient. The tube 21 discharges into a connecting tube 23 communicating with the header 24. If desired, the tube 21 can include and be a part of the tube 23 as shown. Liquid refrigerant thus flows from the valve 19 through the tube under the shelf and thence into the header conduit 24 at the bottom of the unit, from which it is distributed through the expansion ducts 25 into the headers 26. Any oil entrapped with the refrigerant will float on top of the same in the headers 26. As the liquid refrigerant boils off in the header, the gas or vapors therefrom are discharged through the ducts 32 into the suction duct 27 and back to the compressor.

The liquid refrigerant is preferably kept at a level in the evaporator headers 26 beneath the tops thereof.

According to this invention woven wire mesh material such as a copper screen 35 (Figure 6) is rolled into a tight roll 36 to form a capillary active wick. Copper wire of about 80-mesh is highly efficient but it should be understood that other metal wicks can be used in place of woven wire. Fabric wicks are also operable but, since the evaporator unit is formed by a brazing operation at high temperatures, the selected wick material should be capable of resisting the brazing temperature. Asbestos wicks might be used if desired.

The tightly rolled wire mesh wicks 29 are inserted through U-shaped tubes 37 and project from the ends of the tubes. The wick-containing tubes are then inserted through openings provided in the tops of the headers 26 and suction tubes 27 are brazed in place as at 38 (Figure 4). The wicks 29 are also preferably brazed in place in the tubes 37 so that they cannot slip out of place. As shown in Figure 4, the wicks extend into close proximity with the bottom portion of the headers 26 and also extends into the top portion of the suction tube 27. Oil floating on top of the liquid refrigerant in the header passes up the wick 29 by capillary action, through the tube 37 and into the suction tube 27 where it is removed along with the gasified refrigerant. The refrigerant does not flow up the wick by capillary action and, as a result, only the oil is passed through the tubes 37.

If desired a passageway can be embossed on either or both of the metal sheets forming the evaporator unit in place of the tubes 37. The wick 29 can be laid between the sheets in the embossed passageway provided therefor when the sheets are assembled for the brazing operation.

In the modification disclosed in Figures 7 and 8, a U-shaped evaporator unit 40 composed of brazed-together metal sheets bent in the shape of a U has the outer sheet thereof embossed with a plurality of ducts such as expansion ducts 41 extending around the sides and bottom of the unit and communicating with an embossed header 42 in the bottom of the unit and with the embossed cylindrical headers 43 in the top of the

unit. The side walls of the unit are provided with outturned flanges 40a for suspending the unit from the ceiling of a refrigerator cabinet. In place of the embossed suction duct 27 the headers are connected through a suction tube 44 bridging the top portion of the unit. The suction tube 44 communicates with the top portion of each header near one end thereof. The middle of the tube 44 is connected with the tube or duct 28 leading to the compressor of the refrigerating system.

According to the invention a rolled wire mesh screen forming a wick 45 is inserted in the tube 44 with the ends 45a thereof extending into the headers 43 and terminating near the bottom thereof. An intermediate portion 45b of the wick is inserted into the suction tube 28.

In the unit 40 refrigerant is fed into the inlet duct or header 42, passes upwardly through the expansion ducts 41 into the headers 43 from which it boils off or gasifies and the vapors pass through the suction duct 44 into the suction tube 28. However, oil entrained with the refrigerant will float on top of the liquid refrigerant in the headers 43 and will travel upward, by capillary action, through the wick 45 into the suction line 28 where it can be removed together with the gasified refrigerant.

The evaporator unit 40 can be equipped with a sheet metal shelf 46 having downturned side flanges 46a riveted to the side walls of the unit by means of rivets such as 47. The rear end of the shelf can have a downturned central flange portion 46b acting as a stop for articles mounted on the bottom wall of the unit under the shelf. The rear of the shelf can also have an upturned flange 46c on each side of the downturned flange to act as stops for ice trays mounted on the shelf.

From the above descriptions it should be understood that the invention now provides simple, inexpensive wick means for removing oil or other lubricant from heat exchangers such as evaporator units. The invention specifically provides sheet metal evaporator units equipped with wick means between the headers and the suction lines for removing oil from the headers without removing refrigerant before the refrigerant has been completely spent.

In one form of the invention the sheet metal evaporator unit is provided with an embossed suction duct and embossed headers together with a capillary path between the headers and the suction duct. In another form of the invention a stamped sheet metal evaporator unit has the headers thereof joined by a bridging suction pipe for gasified refrigerant and this pipe contains a wick extending into the bottoms of the headers for effecting a flow of oil into the suction line.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. A sheet metal evaporator unit comprising secured-together contiguous metal sheets defining the side walls and bottom of a sharp freezing chamber, at least one of said sheets being embossed to define a header on each side wall, at least one of said sheets being further embossed to define a passageway along the side walls and

bottom of the unit connecting the tops of the headers, and wick devices bridging the headers and the tops of the passageway for removing oil from the headers into the passageway.

2. A sheet metal evaporator unit comprising a pair of secured-together contiguous metal sheets defining the side walls and bottom of a sharp freezing chamber, said sheets being embossed to define a header on each side wall, at least one of said sheets being further embossed to define a passageway joining the tops of each header, a single exhaust communicating with said passageway, means defining additional passageways joining the tops of each header with the tops of said first mentioned passageway, and metal wick members extending through said additional passageways and projecting into said headers and said first mentioned passageway for removing oil from the headers by capillary action.

3. In an evaporator unit composed of inner and outer contiguous secured-together metal sheets defining refrigerant circulation ducts and headers communicating with the ducts together with an embossed flute on one sheet connecting the tops of the headers, the improvement which comprises wick means interposed between the headers and said flute for conveying oil from the headers into the flute.

4. A U-shaped evaporator unit having header chambers in each side wall thereof and a suction tube bridging the side walls and communicating with the tops of each header, the improvement which comprises a wire wick extending through the suction tube into the bottom portion of each header for removing oil from the headers.

5. In a U-shaped evaporator unit having a header chamber in each side wall thereof and a header pipe bridging the space between the side walls and communicating with the top portion of each header, the improvement which comprises a discharge tube communicating with an intermediate portion of said pipe and a wick in said tube and pipe having the ends thereof extending into the bottom portions of said headers and having an intermediate part thereof inserted into said tube.

6. A sheet metal evaporator unit comprising secured-together inner and outer contiguous metal sheets enclosing a sharp freezing chamber and being embossed to provide refrigerant circulating passageways around the chamber, said sheets being further embossed to provide headers at the top ends of said passageways and communicating with the passageways, said outer sheet being further embossed to provide a discharge flute around the sides and bottom of the unit, said inner sheet being embossed to provide a passageway joining the tops of the headers with the tops of said flute, U-shaped metal tubes connecting the tops of the headers with the tops of the flute, and wick means in said U-shaped tubes projecting into the headers and flute for conveying oil out of the headers.

7. In an evaporator unit including means defining a header chamber and means defining a suction line in laterally spaced relation from said header chamber for discharging refrigerant out of the header chamber, the improvement which comprises a U-shaped tube bridging the space between the header chamber and the suction line and having the legs thereof in communication with the header and the suction line, and a tightly rolled wire mesh rod in said tube having the ends thereof projecting from said legs of the tube into the liquid-receiving portion of the

header chamber and into the suction line respectively.

8. A sheet metal evaporator unit composed of U-shaped inner and outer metal sheets secured together in contiguous relation and embossed to provide a header chamber in the top portion of each leg of the U together with refrigerant circulating ducts extending from the header chambers around the sides and bottom of the U, the

improvement which comprises a suction tube for removing gasified refrigerant from the tops of said header chambers and a wick extending through said suction tube into said header chambers for transferring oil out of the header chambers into the suction tube.
